UNITED STATES PATENT OFFICE.

LUDWIG GLANZER, OF WINKLER, KANSAS.

AIR-COOLING DEVICE FOR MULTIPLE MOTORS.

Application filed May 7, 1923. Serial No. 637,185.

To all whom it may concern:

Be it known that I, LUDWIG GLANZER, a citizen of United States, residing at Winkler, in the county of Riley and State 5 of Kansas, have invented certain new and useful Improvements in Air-Cooling Devices for Multiple Motors, of which the following is a specification.

This invention relates to improvements in 10 devices for cooling internal explosion motors, particularly to types in which two or more motor units are arranged side by side and operatively engaged upon a common shaft, and more specifically to motors 15 made in accordance with my co-pending application, filed April, 1923; Serial 634,225, Rotary explosion engines.

One of the objects is to provide a casing 20 or hood arranged to completely envelop the motor units so that a current of air, produced by a fan blower disposed between the units and driven direct by the motor shaft, is caused to circulate around each motor frame dispelling the heat therefrom.

25 Another purpose is to produce a hood that can be easily and quickly raised and removed in case of necessity or convenience, as in inspecting, adjusting or repairing the motors.

30 A further aim is in the provision of means combined with the hood for protecting the spark plugs against injury and through which they are readily accessible.

These aims and objects are attained by 35 the novel construction and combination of parts hereinafter disclosed and shown in the accompanying drawing, forming a part hereof, and in which:—

Figure 1 is a top plan view showing a 40 casing or hood made in accordance with the invention.

Figure 2 is a side elevational view of the same, partially broken away to illustrate its application.

45 Figure 3 is a transverse sectional view taken on line 3—3 of Figure 1 and drawn to an enlarged scale.

In the drawing the numeral 10 designates 50 a platform on which is mounted a pair of motor units 11, each being composed of a pair of rotors having independent connections with the inlet manifold 12 and outlet manifold 13, the former of which receives its gas through the rectangular tube 14, the 55 exhaust gases passing out of a similar tube 15.

All of the several motors are connected with a common shaft 16, horizontally mounted in bearings 17 secured to the platform 10 and having a transmission gear 18 at 60 one or both ends.

Midway between the motor units 11 is a space 19 containing a broad faced fly wheel 20 having a web 21 at its center and lateral spokes 22 flush with the edges of the wheel 65 rim, the hub being fixed on the shaft 16 to rotate with it.

Fixed on the periphery of the wheel are a plurality of extending vanes 23, equally spaced apart and formed at angles, the apex 70 of which is directed in the direction in which the wheel is rotated, thus presenting a herring bone appearance adapted to force air equally in opposite directions.

This wheel is preferably of such diameter 75 as to extend through an opening in the platform, as shown in Figure 3, to gather fresh cool air in its vanes for cooling the motors.

The casing or hood, generally designated by the numeral 24, is composed of a top 80 plate 25 extending completely over the entire motor structure and curved at its edges to blend into the side walls respectively 26 and 27, joined by end walls 28, all of said walls extending downward over the edges of 85 the platform on all sides and secured to them by wing screws 29.

The front plate 26 contains recesses 30 adapted to clear the inlet and outlet connections 14 and 15 and a central recess 31 90 extends in from both side edges to admit air to the fan or vane wheel.

The spark plugs 32 employed on the motors extend upward within the wells 33, the walls of which are open at both ends and 95 secured level within the top plate 25.

From the foregoing it will be seen that 100 an effective device for the purpose has been described in the preferred form of its embodiment, but it will be clear that minor changes may be made without departing from the scope of the appended claims.

Having thus described my invention, what I claim as new and desire to secure by Letters Patent, is:—

1. The combination with a pair of spaced 105 rotary motors operatively engaged on a common shaft, a platform on which said motors are mounted, a flywheel on the shaft between said motors, a series of herring bone 110 vanes on the periphery of said fly-wheel, and a casing disposed over said wheel and

motors, said casing being removably engaged on said platform.

2. The combination with a pair of spaced rotary motors operatively engaged on a common shaft, a platform on which said motors are mounted, a fly-wheel on the shaft intermediate the motors, means on said fly-wheel

adapted to force air laterally outward, and means for confining the air within the vicinity of said motors. 10

In witness whereof I have affixed my signature.

LUDWIG GLANZER.
